MEASURING VALVE

Original Filed Oct. 28, 1926

UNITED STATES PATENT OFFICE

HARRY M. HENDERSON, OF WASHINGTON, DISTRICT OF COLUMBIA

MEASURING VALVE

Original application filed October 28, 1926, Serial No. 144,867. Divided and this application filed November 23, 1927. Serial No. 235,232.

This invention relates to new and useful improvements in dispensing devices, and particularly to devices for dispensing beverages.

The subject-matter of the present application is a division from my pending application filed October 28, 1926, Serial Number 144,867.

One object of the invention is to provide a measuring valve, operable into the beverage of a tank to receive a charge of beverage sufficient to fill a cup, and to be moved outwardly therefrom to discharge such charge into a cup.

Another object is to provide a measuring valve of this character which is constructed in a manner to be manipulated to cause the beverage to flow from the tank into the valve, and whereby to prevent delivery of any amount in excess of the proper charge to fill the cup.

Another object is to provide a valve of this character which will effectively prevent leakage of the beverage from the tank, when the valve is in charge discharging position.

A further object is to provide a valve of this character which will effectively prevent leakage of beverage when the valve is in position to receive its charge from the tank.

Other objects and advantages will be apparent from the following description when taken in connection with the accompanying drawing.

In the drawing:

Figure 1 is a sectional view showing a portion of a liquid dispensing tank, and the measuring valve thereof, said valve being in charge receiving position.

Figure 2 is a similar sectional view showing the valve in charge discharging position.

Referring particularly to the accompanying drawing, 10 represents a portion of a beverage dispensing tank, and screwed into the lower portion of a side of the tank is a cylindrical valve casing 11, said casing projecting into the tank for a short distance, and having its lower side contacting with the bottom of the tank. Removably secured on the outer end of the valve casing is a cap 12, having a central opening 12' in its outer end for a purpose which will presently appear.

In the lower side of said cap there is formed an outlet opening 13, discharging into a spout 14. Slidable in the valve casing 11 is the hollow measuring valve 15, which has a peripheral flange 16, on its inner end, within the tank, to bear against the inner end of the valve casing to effect the positive closing thereof, for the purpose of preventing leakage of beverage from the tank into the space between the valve and casing, should such valve and casing become worn. The outer end of the valve is provided with a similar flange 17, which is screwed into the valve end, and is provided with a stem 18, extending outwardly through the before-mentioned opening 12', said stem being provided with a head 19, and a coil spring engaged on the stem between the head and the said cap. The spring, indicated at 20, serves to hold the valve in withdrawn position, so that the inner flange 16 is seated against the inner end of the valve casing. The valve is provided with openings 21, adjacent its inner end which pass into the beverage, when the valve is moved into the tank, whereby to permit a charge to flow into the valve, while similar openings 22 are formed in the outer portion of the valve for discharging the contents of the valve through the discharge spout 14, when said valve is forced outwardly by the spring 20.

Thus leakage is effectively prevented when the valve is moved inwardly to receive a charge from the tank, and also prevents leakage when the valve is urged outwardly to discharge its charge. This effectively prevents loss of beverage from the tank, in the event that the valve or the casing becomes worn.

What is claimed is:

A liquid dispensing container having a valve casing projecting therefrom, a measuring valve slidable in said casing and having an end adapted to be projected into the container, said valve having openings in its sides adjacent each end, and circumferential beveled flanges on the opposite ends of the valve, one of said flanges normally engaging in closing relation to the inner end of the

casing with the adjacent openings within the casing, the other flange being normally out of engagement with the other end of the casing with the adjacent openings disposed beyond said casing end, and means for yieldably holding the valve in such position.

5 In testimony whereof, I affix my signature.

HARRY M. HENDERSON.
